UNITED STATES PATENT OFFICE.

RUSSELL J. WITTMER, OF CLEVELAND, OHIO, ASSIGNOR TO NATIONAL MALLEABLE AND STEEL CASTINGS COMPANY, OF CLEVELAND, OHIO, A CORPORATION OF OHIO.

TRANSITION DEVICE FOR CAR COUPLERS.

Application filed January 22, 1924. Serial No. 687,673.

Fig. 1 is a plan of the ends of two cars equipped with the old and automatic type couplers and with the transition coupling shown in an inoperative position, the buffers 5 being just in contact; Fig. 2 is an enlarged side elevation of a portion of Fig. 1, including the transition coupling, looking in the direction of the arrow 2 of Fig. 1; Fig. 3 is an elevation of the transition coupling as indicated at Fig. 1 by the arrow 3; Fig. 4 is a similar view to Fig. 1 but with the transition coupling in an intermediate position coupled with a hook coupling and ready to be locked by the lock of the automatic 10 coupler; Fig. 5 is a similar view to Fig. 4 but with the coupling completed and under draft; Fig. 6 is a similar view to Fig. 5 but with the buffers fully compressed; Figs. 7, 8, 9 and 10 show a modified form of transition 15 device, Fig. 7 being a side elevation of the automatic coupling with the transition device attached thereto by connecting members at top and bottom of the coupler head, Fig. 8 being a side elevation of the transition member, Fig. 9 a top plan of the upper connecting member, Fig. 10 a top plan of the lower connecting member, and Fig. 11 a top plan of the modified pin.

My invention relates to transitional coupling mechanism and is particularly designed to provide means for permitting cars equipped with automatic couplers to be coupled with cars equipped with couplers of other types, such as of the draw-hook and side buffer types. To this end I have provided a transitional or supplemental coupling device which can be carried by the automatic coupler and may be easily swung into and out of operative position so that the 40 coupler may be ready for coupling with an automatic coupler of the same type, or with a draw-hook arrangement, or other form of coupler.

My improved mechanism is arranged to be 45 supported by the coupler head at all times. When not in use it is carried at one side of the coupler head. When in use it is swung between the jaws of the coupler head and is there connected with a coupler of the draw- 50 hook type by a device such as a coupling link. My invention also consists in the various features which I shall hereinafter describe and claim.

Referring to the drawings, 2 indicates a 55 couplet of the rigid jaw type shown in the

United States Letters Patent of John Willison No. 1,201,665, dated October 17, 1916, having jaws 3 and 4 and a lock 5 normally projecting forward of the intermediate buffering face 6 of the car coupler. The lock 5 is adapted to be retracted into and projected from a cavity 7 in the coupler head.

The transition coupling mechanism is comprised of a draft member 8, which has an upward extension 9 by which it is supported by a connection 11, preferably slotted, from a carrier casting 10. The pulling jaw 3 of the coupler has a vertical hole 12 for reception of a pin 13 upon which the carrier casting 10 is supported for pivotal movement in a horizontal plane. Mounted in a vertically extending aperture 14 in the forward face of the draft member 8 (when the draft member is in operative position) is a horizontally extending attachment pin 15 70 on which is hung an intermediate link 16. This intermediate link 16 carries a coupling link 17 by which the transitional coupling may be attached to the coupling 21 of a different type. To hold the transitional coupling mechanism in inoperative position, the carrier casting 10 has extending outwardly from its hub a cam projection 18 which cooperates with the cam face 19 on the inner side of the hole 12 through the pulling 75 jaw 3.

I have shown my invention applied to a coupler on cars equipped with buffers 20 and with the opposing car equipped with a coupler 21 of the draw-hook type. In Fig. 1 90 my transition mechanism is shown in inoperative position, in which it is retained by the projection 18 on the carrier casting 10, as the weight of the transition coupling will prevent the projection 18 from riding up 95 the steep forward incline of the cam surface 19. When it is desired to couple the coupler 2 to a draw-hook such as the draw-hook 21, the transition coupling is swung around to the position shown in Fig. 4, in which position the links 16 and 17 can be raised and the link 17 dropped over the draw-hook 21. The draft member 8 is then pushed to the rear, driving before it the lock 5, until it reaches the position shown in Fig. 5, in 105 which the draft member 8 has cleared the lock 5 and the lock 5 has again dropped forwardly to locked position, thus locking the draft member 8 in position. In such position the angled faces 22 bear in the crotch 110

23 of the jaw 3, and the opposite face 24 of the draft member bears against the side face 25 of the lock 5. Also, in such position the draft member 8 has slid to the inner side of 5 the elongated slot 11, in which it is supported in the carrier 10. The elongation of the slot 11 is here necessary to permit the draft member 8 to swing around the tip of the pulling jaw 3 of the coupler 2 and then 10 to slide back into the position shown in Fig. 5. In the position shown in Fig. 5, the slack shown in Fig. 4 to permit the passing of the outer link 17 over the draw-hook 21 has been to a large extent taken up.

15 When, as is shown in Fig. 6, the cars are buffed together with sufficient force to compress the buffers 20 completely, the two links 16 and 17 swing down out of the way and the buffering shock is taken up directly by the 20 buffers 20 without injury to the draw-hook 21 or the transition mechanism.

When the transition coupling is in operative position, as is shown in Figs. 5 and 6, the horizontal flange 27 on the draft member 8 engages the upper edge of the jaw 3 of the coupler, thereby relieving the carrier 10 of the weight of the transitional mechanism.

In uncoupling, the lock 5 is raised, which 30 allows the draft member 8 to swing out to the position shown in Fig. 4. The link 17 may then be disengaged from the draw-hook 21 and the transitional coupling is then 35 swung around to the position shown in Fig. 1, the projection 18 riding up the rear surface of the cam 19 and dropping down its steep forward incline, thus locking the transitional coupling in the inoperative position shown in Fig. 1. If it is desired to remove the transitional member, this may be 40 done by merely taking out the pin 13, which permits the transition coupling to be taken off the automatic coupler 2.

In Figs. 7, 8, 9, 10 and 11 I have shown a modified form of my invention, in which the 45 draft member 28 has extensions 29 at both its top and bottom supported from the carrier castings 30 and 31, which are secured to the pulling jaw 3 of the coupler head by the pin 32. The upper carrier 30 has a flat bearing 33 against the flattened portion 34 of the head of the pin 32, and the lower carrier has a small pin 35 extending horizontally 50 through carrier 31 and pin 32, so that both of the carriers 30 and 31 turn with the pin 32. The use of a support at both the top and 55 bottom of the draft member permits the draft member to be used for direct emergency pulling under extreme conditions of track curvature, which would prevent the 60 member 8 from being swung between the jaws and locked therein.

My improved transitional mechanism provides an extremely simple and economical arrangement for transition service, which 65 may be readily applied to couplers of exist-

ing form and is extremely efficient in operation.

The terms and expressions which I have employed are used as terms of description and not of limitation, and I have no intention, in the use of such terms and expressions, of excluding any mechanical equivalents of the features shown and described, or portions thereof, but recognize that various structural modifications are possible within the scope of the invention claimed.

What I claim is:

1. In coupler mechanism, the combination with a coupler having a reciprocating lock, of a supplemental coupling member pivoted 80 to the coupler and arranged to be rotated therein in a horizontal plane into operative and inoperative positions, the said member when under draft being arranged to transmit draft through, and engaging fixed portions of the coupler and being engaged directly by said lock, said member carrying means for coupling with a coupler of a different type and adapted when in inoperative position to leave said coupler free to couple 90 with another coupler of like type.

2. In coupler mechanism, the combination with a coupler having a reciprocating lock, of a supplemental coupling member supported on a pin mounted on a jaw of said 95 coupler and adapted to be rotated thereabout in a horizontal plane into and out of operative position, the said member when under draft being arranged to transmit draft directly through and engaging fixed portions 100 of said coupler other than the portions engaged by the pin and being directly engaged by said lock, said draft member carrying means for coupling with a coupler of a different type.

3. In coupler mechanism, the combination with a coupler of a supplemental coupling member, said supplemental coupling member having a horizontal arm pivoted to the coupler head upon which the member rotates 110 into and out of operative position in a horizontal plane to engage a pulling surface on the coupler head, the said member being held in operative position and in engagement with the pulling surface on the coupler head by direct contact with the lock of the coupler.

4. In coupler mechanism, the combination with a coupler of a supplemental coupling member, said supplemental coupling member having an arm pivoted to the coupler head upon which the member moves into and out of operative position in a horizontal plane and into and out of engagement with a pulling 120 surface on the coupler head, the said member when under draft being arranged to transmit draft through said pulling surface of said coupler, said supplemental coupling member having also a lateral extension 125 which engages the coupler head and 130

by which it is supported when in operative position.

5. In coupler mechanism, the combination with a coupler having a reciprocating lock, of a supplemental coupling member pivoted to the coupler and arranged to be rotated therein into operative and inoperative positions, the said member when under draft being arranged to transmit draft through and engaging fixed portions of the coupler and being engaged directly by said lock, said member carrying an intermediate coupling member mounted for free movement in a vertical plane for coupling with a coupler of a different type.
6. In coupler mechanism, the combination with a coupler having a reciprocating lock, of an intermediate coupling member for coupling to a coupler of a different type; a supplemental coupling member on which the intermediate member is mounted; the supplemental coupling member being pivoted to the coupler and being capable of rotation about the coupler head to permit the intermediate member to be coupled with a coupler of a different type, and of further rotation

into operative draft position to take up the slack of the connection of the intermediate member with the other coupler; the said supplemental member when in operative 30 draft position engaging fixed portions of the coupler and being engaged directly by said lock.

7. In coupler mechanism, the combination with a coupler having a reciprocating lock 35 of a supplemental coupling member pivoted to the coupler and arranged to be rotated therein into operative and inoperative positions; the said member when under draft being arranged to transmit draft through 40 and engaging fixed portions of the coupler and being engaged directly by said lock, said member carrying an intermediate coupling member for coupling with a coupler of a different type, the movement of the supplemental member into engagement with the lock and fixed portions of the coupler comprising means for taking up the slack in the intermediate member after coupling with a coupler of a different type.

RUSSELL J. WITTMER.
